UNITED STATES PATENT OFFICE.

EVERETT H. WALKER, OF LOWELL, MASSACHUSETTS, ASSIGNOR TO LAWRENCE MANUFACTURING COMPANY, OF LOWELL, MASSACHUSETTS, A CORPORATION OF MASSACHUSETTS.

CIRCULAR-KNITTING MACHINE.

1,034,665.

Specification of Letters Patent.

Patented Aug. 6, 1912.

Application filed April 13, 1911. Serial No. 620,739.

To all whom it may concern:

Be it known that I, EVERETT H. WALKER, a citizen of the United States, residing at 121 Hall street, Lowell, in the county of Middlesex and State of Massachusetts, have invented certain new and useful Improvements in Circular-Knitting Machines; and I do hereby declare the following to be a full, clear, and exact description of the invention, such as will enable others skilled in the art to which it appertains to make and use the same.

The invention relates to circular knitting machines for knitting split foot stockings.

15 The object of the invention is to provide a novel and improved construction and arrangement of the devices for operating and controlling the needles and for controlling the feed of the yarn to the needles, whereby 20 the feed of the black yarn to the needles may be continued during a part or all of the narrowing in knitting the heel, so that a drop heel or a split heel stocking may be knit.

25 The invention is intended primarily as an improvement on the construction of machine shown and described in the patent to Paquette No. 985,927, dated March 7, 1911, although it will be understood that the invention is not limited in its application to this machine, and that it may be embodied in other forms of circular knitting machines for producing seamless split foot hosiery.

The invention consists in the features and 35 combinations hereinafter described and referred to in the claims.

The various features of the invention will be understood from an inspection of the accompanying drawings, and the following 40 detailed description of the machine illustrated therein.

In the drawings Figure 1 is a left-hand side elevation of a knitting machine embodying the invention in its preferred form; Fig. 2 is a front elevation of the machine; Fig. 3 is a detailed side elevation of the devices for controlling the yarn changing guides; Fig. 4 is a detailed elevation showing the cam for controlling the needle depressing or widening pickers; Fig. 5 is a detailed elevation showing the mechanism for actuating the shaft which carries the 50 mechanisms of the machine; Fig. 6 is a view showing an interior development of the cams 55

and needle operating devices in position for rotary knitting; and Fig. 7 is a view showing a development of the cams for actuating the yarn guides which deliver the yarn to the knitting waves formed by the main 60 knitting cams and also the cam for moving the main sinker cam in and out.

The machine shown in the drawings has the same construction and mode of operation as the machine shown and described in the patent above referred to, except so far as this construction and mode of operation is changed and modified by the incorporation of the present improvements in the machine. In this machine the needles 1 are of 70 the type known as latch needles, and are carried in a needle cylinder 2 which is mounted for rotary and reciprocatory movement and the needles are operated and controlled during the knitting by cams carried by a cam plate 3 which may be moved vertically to control the length or tightness of the stitch drawn by the needles. The needles are divided into two substantially semi-circular groups, one group being provided 80 with long butts, and the other group with short butts, the two series overlapping to provide short and long butt suture needles, as fully disclosed in the above patent. The devices carried by the cam plate 3 are the 85 same in construction and mode of operation as the devices shown and described in the above patent and comprise the main stitch cams 4, the supplemental stitch cams 5, the needle elevating or narrowing pickers 6, the 90 needle depressing or widening pickers 7, the cams 8 and 9 for raising the instep needles into the inactive plane and returning them to the active plane, the needle depressing cams 10 for directing the long butt needles 95 down into the supplemental knitting cams during the knitting of the foot, the cam 11 for elevating the long butt needles during the knitting of the foot, the cams 12 for completing the downward movement of 100 the short butt needles depressed by the cams 10, and the supplemental picker 13 for raising the rear short butt suture needle into the inactive plane during the first reverse stroke on the heel and toe. The cam carrying plate 3 is supported upon a vertical sliding bar 14 which may be raised or lowered to tighten or loosen the stitches drawn by the knitting cams. The vertical position of the bar 14 and cam carrying plate 3 is con- 110

trolled by cams formed on a cam disk 15 secured to the cam shaft 16, and arranged to act upon pins 17 carried by an arm 18 secured to the bar.

5 The supplemental cams 5 are moved radially outward to bring them into position to act upon the long butts only, or radially inward into position to act upon both the long and short butts, by means of a lever 19 connected by a link 20 with the bell crank lever 21 which raises and lowers the cams 8 and 9. The bell crank lever is connected by means of a link 22 with the clutch shifting lever 23, so that cams 8 and 9 are raised to throw up the long butt needles and the supplemental cams are withdrawn from the path of the short butts when the motion is changed from rotary to reciprocating at the beginning of the heel, and cams 8 and 9 are lowered to return the inactive needles to the active plane and the supplemental cams advanced to act upon all the needles when the motion is changed from reciprocating to rotary at the completion of the toe.

25 The needle depressing or widening pickers 7 are raised and lowered to render them active or inactive at the proper time by a cam 24 on the cam shaft 16 which is arranged to engage one end of a lever 25. The other end of the lever is connected by a link 26 with a lever 27, the end of which engages the lower end of the pin 28. The upper end of the pin carries the plate 29 which is arranged to engage the depressing pickers and move them into and out of active position. The picker 13 is thrown into action at the beginning of the heel and at the beginning of the toe by pins 30 arranged to engage one end of a lever 31, the other end of which is connected to the picker actuating rod 32. The wing cams 10 are advanced at the completion of the heel and retracted at the completion of the foot by a cam lug 33 arranged to engage the end of a lever 34 which is connected to the actuating slide 35 by the link 36, bell crank lever 37, and link 38.

50 The web holding sinkers are retracted and advanced at the knitting points by main and supplemental sinker cams mounted in the sinker cam ring 39. The sinker cams are radially movable and are pressed inward into inactive position by springs 40 and 41. The main sinker cam is held out in its active position so that it acts to withdraw the sinkers at the knitting point by a bell crank lever 42 which is connected by a cord 43 with the rear end of a lever 44. The front end of the lever 44 rides on an annular cam rib 45 carried by the cam shaft 16. The cam rib is provided with a short depression 46 which registers with the end of the lever 44 and allows the sinker cam to move inward into inactive position during the running off of a completed stocking and the beginning of a new stocking. After a few

courses have been knit on the new stocking, the lever 44 rides on to the high part of the cam rib 45, so that the sinker cam is held in active position during the knitting of the stocking. The supplemental sinker cam is held in active position against the tension of the spring 41 by a cam finger 47 formed at the upper end of a vertically sliding rod 48. The rod is connected with an actuating lever 49 the movements of which are controlled by a cam 50 secured to the cam shaft 16 and arranged to engage one end of a lever 51, the other end of which is connected by a link 52 with the lever 49. The cam 50 is recessed to withdraw the cam finger 47 and allow the supplemental sinker cam to move radially inward into inactive position so that it will not withdraw the sinkers during the knitting of the heel and toe, and during the running off of a completed stocking and the beginning of a new stocking.

90 The latch ring 53 is provided with a yarn guide 54 through which black yarn is fed to the knitting wave formed by the supplemental knitting cams during rotary knitting on the leg and during reciprocatory knitting on the foot. The yarn B' leads from the thread guide through a thread guide 55 formed in an overhanging arm arranged above the knitting head and thence through a spring actuated takeup 56, through thread guides 57 and 58, and through a tension device 59 which is arranged over the supply cap 60. Either black or white yarn is fed to the knitting wave formed by the main knitting cam by means of a series of three guides 61. These guides are pivoted at 62 so that they may be raised to withdraw the yarn from the needles, or may be lowered to feed the yarn to the knitting wave. They are held in active or yarn feeding position by springs 63, and are raised to withdraw the yarn by a series of levers 64. When one or more of the yarn guides are raised to withdraw the corresponding yarn or yarns from the needles, the yarn or yarns not being fed to the needles is held inside the needles by a retainer 65, so that the yarn is properly presented to the needles when the guide is again moved down into active position. The retainer is lifted to allow the yarn to pass under it by a lever 66 which is operated by an upward movement of one of the yarn guides, and is immediately released by a short downward movement of the guide so that the retainer immediately engages and holds the yarn. The levers 64 for raising and lowering the yarn guides 61 are connected by cords 67 with levers 68, 69 and 70. The lever 68 is connected to operate the guide for the black yarn B. The lever 69 is connected to operate the main white yarn W, and the lever 70 is connected to operate the guide for the supplemental white yarn 100

110

130

w. The levers 68, 69 and 70 are operated to control the feed of the yarn to the knitting wave formed by the main knitting cams by the cam ribs 71, 72 and 73 respectively which are carried by the cam shaft 16 and are arranged parallel to the cam rib 45 for actuating the main sinker cam. The cam ribs 71, 72 and 73 are so shaped and arranged, and the cam shaft 16 is so actuated that the black yarn B, is fed to the needles during the knitting of the leg of the stocking, and is also fed to the needles during a part at least of the narrowing on the heel. After the heel has been partially completed the yarn guides are actuated to withdraw the black yarn and to feed the white yarns W w to the needles during the completion of the heel. The white yarn w is withdrawn at the completion of the heel, and the main white yarn W is fed to the knitting wave formed by the main knitting cams during the knitting of the foot. At the completion of the foot the supplemental white yarn w is again fed to the needles with the main white yarn, and the feed of these yarns to the needles continues during the knitting of the toe. At the completion of the toe the supplemental white yarn w is again withdrawn, and the main white yarn is fed to the needles for a number of courses of rotary knitting. Then all the yarn guides are raised to run off the completed stocking, and immediately thereafter the guide for the black yarn is returned to position to feed the black yarn to the needles during the knitting of the leg of the succeeding stocking. The cam rib 71 is provided with a lug 74 for raising the guide for the black yarn B sufficiently to lift the yarn retainer 65 when the black yarn is withdrawn from the needles, and the cam rib 72 is provided with a lug 75 for raising the guide for the white yarn W sufficiently to raise the retainer 65 just after the main white yarn is withdrawn from the needles, so that the white and reinforce yarn may pass under the retainer. The yarns B, W, w pass through suitable guides above the knitting head, and each of the yarns is led through a spring takeup which acts to keep the yarn taut while it is being fed to the needles during reciprocatory knitting.

The cam shaft 16 is intermittently fed during the knitting of a stocking to automatically actuate and control the devices for operating upon the needles and feeding the yarns, by a pawl 76 arranged to engage teeth formed in a ratchet wheel 77 which is secured to the cam shaft. The pawl is carried by the oscillating segment 78 of the motion changing mechanism so that it is continuously reciprocated, and the pawl is normally held out of engagement with the teeth of the ratchet wheel by a guard lever 79. The guard lever is held in normal position by a spring 80, and is rocked to allow

the pawl 76 to engage the teeth of the ratchet wheel by a series of lugs formed on a pattern chain 81 and arranged to engage a lug 82 on the lever. The pattern chain is carried on a sprocket wheel which is loosely mounted on the cam shaft, and is fed during the operation of the machine by a pawl similar to the pawl 76 which engages a ratchet wheel 83 secured to the sprocket wheel. The teeth on the ratchet wheel 77 are of varying lengths, and the lugs on the pattern chain are of the proper length and properly arranged to rock the guard lever so that the pawl will properly engage the tooth of the ratchet wheel which is in position to be engaged by it when the guard lever is rocked. When there is to be a comparatively short forward feed of the cam shaft, a short lug, such as shown at 84 engages the lug 82 on the guard lever and rocks the lever sufficiently to expose one of the short teeth on the ratchet wheel 77. When a comparatively long feed is to take place; a long lug such as shown at 85 rocks the guard lever sufficiently to enable the pawl to engage one of the long teeth on the ratchet wheel. At intervals during the knitting of the stocking the ratchet wheel and cam shaft are given a short feed and then a long feed immediately following the short feed. At such times a double lug, such as shown at 86, acts upon the guard lever 79. The low part of the double lug first rocks the guard lever to expose a short tooth, and then the high part of the double lug rocks the lever to a greater extent to expose the succeeding long tooth on the ratchet wheel.

Assuming that the machine is operating to knit the upper part of the leg of a stocking, the levers 44, 68, 69 and 70 will be at the point indicated at 87 in Fig. 7. The guides for the white yarns W, w will be raised, and the guide for the black yarn B will be in position to feed the yarn to the needles. The lever 25 which controls the widening pickers will be on the high part 24' of the cam 24, and the widening pickers will be up in active position. At this time the tooth 77' of the ratchet wheel 77 will be at the point O in position to be engaged by the pawl 76 when the guard lever is rocked to uncover the tooth. During the knitting of the leg of the stocking the pawl 76 acts upon the tooth 77' and the five short teeth immediately following it, and feeds the cam shaft forward so that the fashioning cams on the disk 15 vary the height of the plate 3 and knitting cams to fashion the leg of the stocking. During these feeding movements of the cam shaft the lever 68 continues to ride along the low part 71a of the cam rib 71 while the levers 69 and 70 continue to ride on the high parts 72b and 73b of the cams 72 and 73, and the lever 25 continues to ride on the high part 24' of the cam 24.

When the heel is reached, the pawl 76 is engaged with the short tooth 77² to give the cam shaft a short feed, and is then immediately engaged with the long tooth 77³ to give the cam shaft a long feed. During the short feed the speed of the machine is changed by the speed changing cam, the supplemental sinker cam is thrown out of action, and the picker 13 is thrown into action. During the long feed the clutch lever 23 is shifted by its cam to change the motion of the needle cylinder from rotary to reciprocating. The lever 25 during the long feed also rides into the recess 24² of the cam 24, so that the widening pickers are moved down out of active position. The shifting of the clutch lever 23 raises the cams 8 and 9 to throw the long butt instep needles up into the inactive plane, and the narrowing begins. At this time the yarn levers 68, 69 and 70 are at the point indicated at 88 in Fig. 7, and the black yarn is still fed to the knitting wave formed by the main knitting cams.

In order that that part of the heel which is knit with the single black yarn may have the same appearance as that part of the heel which is knit by the main white yarn and the reinforce yarn, the cam carrying plate 3 is raised to tighten the stitch in going on to the heel. For this purpose the cam disk 15 is provided with a projecting lug 89 which is brought under one of the pins 7 by the long feeding movement just described, and which remains under this pin until the cam shaft is given its next movement.

After the narrowing has been partly completed the pawl 76 is engaged with the short tooth 77⁴ and the cam shaft is given a short feed. During this feed the yarn levers 69 and 70 ride off the high parts 72^b and 73^b of the cams 72 and 73, and fall into the low parts 72^a and 73^a, thus engaging the white yarns W, w with the needles. Immediately thereafter the yarn lever 68 rides up to the high part 71^b of the cam rib 71, thus withdrawing the black yarn. In passing on to the high part 71^b the lever passes over the lug 74 so that the retainer 65 is raised to allow the black yarn to pass under it, and is then immediately dropped to retain the yarn. After this feed the yarn levers are at the point indicated at 90 in Fig. 7. In order that this feeding movement of the cam shaft may not throw the widening pickers into operation, the recess 24² in the cam 24 is of such length that the lever 25 still remains in the recess after the feeding movement has been completed. At the end of the narrowing the pawl 76 engages the short tooth 77⁵ and gives the cam shaft a short feed to bring the end of the lever 25 up on to the high part 24⁴ of the cam 24, and thus raise the widening cams into active position. During this feed the yarn lever

70 corresponding to the reinforce white yarn w still rides in the low part 73^a of the cam 73, and the reinforce yarn continues to be fed to the needles during the widening on the heel. At the completion of the heel, the pawl 76 engages the long tooth 77⁶ and gives a long feed to the cam shaft. During this feed the wing cams 10 are thrown into action, the supplemental sinker cam which has been out of action during the knitting of the heel is thrown into action, and the lever 70 corresponding to the reinforce yarn w rides up on to the high part 73^b of the cam 73, so that the reinforce yarn is disengaged from the needles. At the completion of the feed the pawl 76 engages the short tooth 77⁷ and gives the cam shaft a short feed, and then immediately engages the long tooth 77⁸, and gives the cam shaft a long feed. During the short feed the supplemental sinker cam is moved inward out of active position, the wing cams 10 are moved out of active position, and the picker 13 is thrown into action. During the long feed the yarn lever 70 rides into the low part 73^a of the cam 73, so that the reinforce yarn w is fed to the needles during the knitting of the toe. During this long feed also the lever 25 rides into the recess 24⁴ of the cam 24, so that the widening pickers are moved down into inactive position, and the narrowing on the toe begins. After the narrowing is completed the pawl 76 engages the short tooth 77⁹, and gives the cam shaft a short feed. During this feed the lever 25 rides up on to the high part 24⁵ of the cam 24, so that the widening pickers are thrown into action. At the completion of the widening the pawl 76 engages the long tooth 77¹⁰, and gives the cam shaft a long feed. During this feed the speed is changed, and the clutch lever is shifted to change the motion from rotary to reciprocating. The supplemental sinker cam is thrown into action, and the yarn lever 70 rides up on to the high part 73^b of the cam 73, thus discontinuing the feed of the reinforce yarn w to the needles. At the end of this feed the yarn levers are at the point indicated at 91 in Fig. 7. The yarn lever 69 is still in the low part 72^a of the cam 72, and the lever 68 is still on the high part 71^b of the cam 71, so that the white yarn W is still fed to the needles. For a few courses of rotary knitting, white yarn is therefore fed to the knitting wave formed by the main knitting cams, and black yarn to the knitting wave formed by the supplemental knitting cams. After a few courses have been knit the pawl 76 engages the tooth 77¹¹, and gives the cam shaft a long feed. During the first part of this feed the yarn lever 69 rides on to the high part 72^b of the cam 72, and the lever 68 still remains on the high part 71^b of the cam 71, so that no yarn is fed to the knitting wave formed by the

main knitting cams, and consequently the finished stocking is run off the needles. During the latter part of this feed the yarn lever 68 rides off the end of the high part 5 71^a and drops into the low part 71^b, so that the black yarn B is fed to the wave formed by the main knitting cams. During the latter part of this feed the lever 44 through which the main sinker cam is operated enters the recess 46 in the cam rib 45, so that the main sinker cam is out of action during the running on of the loops at the beginning of the new stocking. The supplemental sinker cam is also out of action at this time. 10 15 After a few courses have been knit the pawl 76 engages the short tooth 77^b, and gives the cam shaft a short feed. During this feed both sinker cams are thrown into action, and the lug 75 acts to raise the yarn guide for the white yarn W for an instant, so that the retainer 65 is lifted to allow this yarn and the reinforce yarn w to pass under it, and is then released to hold the yarns. 20 25 This feeding movement completes the revolution of the cam shaft, and completes the cycle of operations performed in knitting each stocking.

While it is preferred to employ the specific construction and arrangement of the parts shown and described in embodying the invention in the machine shown in the patent referred to, it will be understood that this construction and arrangement are not essential except so far as referred to in the 30 35 claims, and may be varied or modified without departing from the invention.

Having explained the nature and object of the invention, and specifically described one form of mechanism in which it may be 40 embodied, what I claim is:—

1. A circular knitting machine for knitting split foot stockings, having, in combination, semi-circular series of needles having long and short butts respectively, main knitting cams, supplemental knitting cams arranged to act on all the needles during rotary knitting on the leg, needle lifting and depressing pickers, mechanism for rendering the supplemental cams inactive on the short 45 50 55 60 65 butt needles during reciprocatory knitting, devices for rendering the long butt needles inactive during reciprocatory knitting on the heel and toe, devices for rendering the supplemental knitting cams active on the long butt needles during reciprocatory knitting on the foot, a yarn guide for feeding black yarn to the knitting wave formed by the supplemental knitting cams, a plurality of yarn guides for feeding black or white 70 75 80 85 90 95 100 105 110 115 120 125 130 135 140 145 150 155 160 165 170 175 180 185 190 195 198 200 205 210 215 220 225 230 235 240 245 250 255 260 265 change from rotary to reciprocatory knitting and to return the main knitting cams to their lower position to loosen the stitch upon the movement of the guides to feed 5 the main and reinforce white yarns to the needles, substantially as described.

4. A circular knitting machine for knitting split foot stockings, having, in combination, a needle cylinder, needles therein comprising two semi-circular groups, cams for 10 operating each group of needles, narrowing and widening devices, mechanism for rendering the cams for both groups active on all the needles during rotary knitting and the 15 cams for each group active upon its own group during reciprocatory knitting, means for rendering one group of needles inactive during the narrowing and widening, a yarn guide for feeding yarn to the knitting wave 20 formed by the cams which are inactive dur-

ing the narrowing and widening, a plurality of yarn guides for feeding yarn to the knitting wave formed by the cams which are active during the narrowing and widening, a cam shaft carrying cams for controlling said 25 mechanisms and devices, means for advancing the cam shaft at the beginning of the heel, cams on the shaft for operating the yarn guides arranged to maintain the guides in position during this advance movement 30 of the cam shaft, and means for advancing the cam shaft during the knitting of the heel to shift the yarn guides and change the yarn from black to white, substantially as described.

EVERETT H. WALKER.

Corrections in Letters Patent No. 1,034,665.

It is hereby certified that in Letters Patent No. 1,034,665, granted August 6, 1912, upon the application of Everett H. Walker, of Lowell, Massachusetts, for an improvement in "Circular-Knitting Machines," errors appear in the printed specification requiring correction as follows: Page 4, line 115, for the word "arm" read *cam*; page 6, line 16, after the word "group" insert the word *only*; and that the said Letters Patent should be read with these corrections therein that the same may conform to the record of the case in the Patent Office.

Signed and sealed this 22d day of October, A. D., 1912.
